UNITED STATES PATENT OFFICE

LE ROY C. SCHENCK, OF MOLINE, ILLINOIS, ASSIGNOR TO TROY LAUNDRY MACHINERY COMPANY, INC., OF NEW YORK, N. Y., A CORPORATION OF DELAWARE

LIQUID LEVEL CONTROL FOR WASHING MACHINES

Application filed December 28, 1928. Serial No. 328,946.

This invention relates to laundry machinery and in particular to laundry washing machines of the type employing a garment container in the form of a cylinder, rotating within an outer casing serving as a liquid container.

The invention has for its object to provide means for accurately and automatically determining and maintaining the level of liquid to be used in the outer casing of a washing machine of the above noted type.

Laundry washing machines may be divided into two principal types, the first being adapted for washing with a liquid element consisting mainly of water; the second being adapted for dry cleaning and many more volatile liquid solvents such as benzene, naptha, gasoline, etc. This invention, while useful with either type of machine, is particularly advantageous when applied to machines of the latter type.

Heretofore in dry cleaning washers it has been customary to provide an inlet connection at the top of the machine for the incoming solvent, an outlet connection at the bottom for draining the solvent from the machine and a stationary outlet immediately below the cylinder journal to prevent the solvent level from rising to the height of the journal and leaking from the outer casing or container at this point. When such a machine is used with the most common dry cleaning process, known as "continuous flow", the level of the solvent in the washer is maintained by the adjustment of the inlet and outlet valves, the stationary overflow being relied upon to prevent the solvent from reaching too high a level within the machine. With such an arrangement it will be seen that the height of the liquid level is more or less indefinite and depends entirely upon the care used in the relative adjustments of the inlet and outlet valves.

Then again, it is sometimes customary to use an overflow outlet as a drain to maintain a definite height of liquid level, allowing the drain connection at the bottom of the container to remain closed.

With either method it will be seen that there is no provision for the maintenance of

a constant liquid level together with the feature of making it possible to vary this constant liquid level at the option of the operator. Accordingly, it is a feature of the present invention to provide an attachment for washing machines which is capable of being adjusted to different positions positively to prevent the liquid level within the machine from rising above the predetermined point.

Other features and advantages will be apparent after a consideration of the following description and the appended claim.

Referring to the drawings, Fig. 1 shows the invention applied to one well known form of washing machine employing a horizontally disposed cylinder and casing.

Fig. 2 is a front elevation of the machine shown in Fig. 1.

Referring more particularly to Fig. 1, numeral 1 indicates generally the outer casing of a washing machine of known construction which is preferably completely closed except for the usual charging door at the front of the machine. Mounted in any convenient manner for rotating within the casing 1 is a perforated tumbling cylinder 2. The outer casing 1 as shown in the drawings is supported on suitable standards 3.

The lowermost part of the outer casing is provided with a drain outlet 4 and a drain valve 5 of any suitable type. At any point preferably above the highest liquid level to be used there is provided an inlet pipe 6 which is connected to a source of liquid washing material. At one lower end of the casing there is provided an outlet pipe 7 which is joined to an overflow unit 9 having an inverted U shaped liquid channel. The preferred construction of this overflow unit comprises a hollow cylindrical member 9 having its interior divided into two separate chambers by means of a baffle plate 10. Member 10 is shorter than the interior length of member 9 to provide an overflow communication from one chamber to the other. This arrangement may be called a closed U-bend. The lower exterior end of member 9 at opposite sides is provided with threaded extensions 11 and suitable unions 12 are provided for uniting

the threaded extension 11 on one side to the outlet pipe 7 and on the other side to the drain pipe 13. The unions 12 are of suitable type to permit the member 9 to be rotated angularly with respect to the pipe 7. For the purpose of preventing the liquid in the casing 2 from being siphoned out the member 9 is provided with a suitable vent 14 at the top thereof.

10 While the drawings disclose the preferred embodiment of the overflow unit, it will be understood that other equivalent constructions might be employed. For example, the unit may take the form of an ordinary U-bend which is of sufficient length to enable the liquid to rise to the maximum desired height within the casing 2.

Member 9 together with baffle plate 10 are preferably of such height that when in the vertical position, the liquid within the casing is capable of rising to the maximum desired height. On the other hand, if member 9 is rotated to the position shown in the dotted lines (Fig. 1), the liquid level will be greatly lowered. This position should be such as to afford the minimum liquid level with which satisfactory washing will be obtained. In any intermediate position, therefore, of member 9, the liquid within the casing will rise to the height determined by the height of the baffle plate 10, and any excess of liquid above this level will flow out by gravity through the pipe 13 to a suitable reservoir. With this arrangement, a positive control of liquid level is provided even though the operator should improperly adjust the inlet or outlet valves. The height of the liquid will never exceed that which has been predetermined by the position of the overflow unit 9.

40 If desired, a suitable pointer 15 may be attached to member 9 and in cooperation therewith a corresponding scale 16 graduated to read in suitable units of liquid height may be attached to the end of the machine whereby the attendant will be enabled to accurately gauge the angular position of member 9 in accordance with the height of the liquid desired within the casing. The member 9 therefore provides an automatic, positive and readily adjustable means for preventing the level from rising beyond a predetermined height, whether this member be used as a drain for the machine when the liquid is flowing continuously or whether it is used merely as a safety measure to prevent the rise of the liquid level beyond a predetermined height.

60 While the invention is closed in connection with one particular type of washing machine, it will be obvious to those familiar with the art that it may be equally well applied to other well known types of washing machines without departing from the spirit and scope of the invention.

What I claim is:

In a laundry machine an outer casing serving as a container for a liquid washing agent, a substantially horizontal liquid discharge conduit connected to said casing to discharge said liquid from near the bottom thereof, an elongated hollow member having one end closed and the other end connected between adjacent portions of said discharge conduit and having inlet and outlet openings communicating with said conduit, means rotatably connecting said hollow member to said portions of said discharge conduit to permit swivelling of the hollow member in a substantially vertical plane, and means within said hollow member dividing its interior longitudinally into separate chambers having open communication with each other at their upper ends.

In testimony whereof, I have signed my name to this specification, this 6th day of December, 1928.

LE ROY C. SCHENCK.
